UNITED STATES PATENT OFFICE.

WILLIS A. TRECOTT, OF FAIRPORT, NEW YORK, ASSIGNOR TO THE TRECOTT COMPANY, INC., OF FAIRPORT, NEW YORK, A CORPORATION OF NEW YORK.

SORTING OR GRADING MACHINE.

Application filed September 9, 1918. Serial No. 253,150.

To all whom it may concern:

Be it known that I, WILLIS A. TRECOTT, a citizen of the United States, residing at Fairport, in the county of Monroe and State 5 of New York, have invented certain new and useful Improvements in Sorting or Grading Machines; and I do hereby declare the following to be a full, clear, and exact description of the invention, such as will enable others skilled in the art to which it ap- 10 pertains to make and use the same.

My present invention relates to sorters or graders and has for its object to provide a machine particularly adapted for grading elongated fruits or vegetables, and particularly what are known as "Burbank" potatoes, the longitudinal section of which is, generally, elliptical in form. It consists generally speaking, of one or more endless 15 conveyors having elongated apertures or openings therethrough with the longer dimensions in the direction of travel, and preferably means for causing the articles to be graded to be arranged in proper position over the apertures so as to be gaged by their 20 length, and also consists in certain improvements and combinations of parts all as will be hereinafter more fully described, the novel features being pointed out in the 25 30 claims at the end of the specification.

In the drawings:

Figure 1 is a longitudinal section of a machine embodying my improvements,

Figure 2 is a plan view of the same,

Figure 3 is a view similar to Figure 1, showing a modified form of aligning device,

Figure 4 is a cross sectional view on the line $x-x$ of Figure 3,

Figure 5 is a cross sectional view on the line $y-y$ of Figure 1,

Figure 6 is a perspective view of one of the links of a conveyor, and

Figure 7 is a sectional view showing the means for connecting the links.

Similar reference numerals in the several views indicate the same parts.

As shown in Figures 1 and 2 the machine comprises, generally, framework indicated by 1, having supporting legs 2 and an open-ended hopper at the upper side of one end of the frame comprising an inclined end 3 and sides 4, into which the vegetables or other articles to be graded are deposited. 5 and 5^a indicate rollers in the ends of the frame,

around which extend a plurality of endless 55 conveyors, each composed in the present instance of open links 6, such as shown in Figure 6, the openings through which are elongated or elliptical and at the ends are provided eyes 7, and connecting the eyes of 60 adjacent links are short, flat, imperforate links 8. In the present embodiment I have shown four such conveyors, and between them are arranged separating bars 9 having inclined tops as shown, said separators and 65 the conveyors constituting not only the bottom of the receiving hopper but a support for the articles to be graded and separated. The conveyors are supported upon rollers 11, 70 arranged intermediate the rollers 5 and 5^a, 75 and are preferably driven from the roller 5^a at the discharge end, which is provided with an operating handle 12. Said roller or drum 5^a is also provided with projections 13 thereon spaced to substantially correspond with the openings in the links 6 and serving not only to operate the conveyors 80 in the direction of the arrow (Fig. 1), but also to remove from the links any vegetables which might have become lodged therein. 85 As the purpose of this machine is to support elongated or elliptical articles, such as Burbank potatoes, it is desirable to cause such articles to be straightened or brought into substantial alignment with the grading 90 openings and for this purpose I provide adjacent the tops of the supporting strips 9, pins 15 or projections for engaging the ends of any vegetables or articles that may extend transversely of the conveyors, and 95 with which they contact during their travel through the machine. In the preferred embodiment of the invention, these pins 15 are stationary and are located on the tops of the separating strips in staggered relation so as 100 to engage the ends of the articles, if they should extend crosswise of the conveyor, so that as they are carried by the latter they will be straightened with their greater dimension extending in the direction of travel 105 and thus be gaged by the longer dimension of the openings in the links 6. The smaller vegetables will pass through the conveyors, falling upon a chute or support 25 and be deposited at the side of the machine, while 110 the larger vegetables, which it is the object of the machine to remove, are carried to the end of the frame and discharged, each hav-

ing been tested by the aperture through the link 6, in which it rests, and by which it is carried.

Instead of causing the articles to be aligned with the gaging apertures in the conveyor solely by the movement of the conveyors, I may employ the arrangement shown in Figures 3 and 4 embodying the belts 16, extending over and parallel with the separating strips 9 and carrying aligning pins or projections 17, said belts passing around grooved rollers 18 and 18^a, the latter being driven in the direction of the arrow in Figure 3 by a belt 20 from a pulley on the shaft of the roller 5^a. By operating the belts 16 in the opposite direction from that of the conveyors, the articles may be more quickly aligned, but by reason of the simplicity of the arrangement wherein the pins are stationary, I prefer that, although in both the result is accomplished by the relative movements of the articles and the pins.

Having described my invention, what I claim and desire to secure by Letters Patent is:

1. A grading machine for articles of substantially elliptical outline comprising a traveling conveyor having a plurality of openings therethrough elongated in the direction of movement of the conveyor and projections adjacent the sides of the openings for engaging and aligning the conveyed articles with said openings.

2. A grading machine for articles of substantially elliptical outline comprising a traveling conveyor composed of separate, rigid, elliptical open links with their greater length extending in the direction of travel, flexible connections between the links and projections adjacent the sides of the conveyor for engaging and aligning the conveyed articles with said links.

3. A grading machine for articles of substantially elliptical outline comprising a traveling conveyor having a plurality of sub-

stantially elliptical openings therethrough arranged in parallel rows with their greater dimensions extending in the direction of travel and a plurality of projections arranged between the longitudinal rows adapted to align the articles carried by the conveyor with the apertures in the latter.

4. A grading machine for articles of substantially elliptical outline comprising a traveling conveyor having a plurality of rows of substantially elliptical openings therethrough, the longer dimensions of the openings extending in the direction of travel, separating strips arranged between longitudinal rows of openings and projections adjacent said strips for engaging and aligning articles carried by the conveyor with said openings therein.

5. A grading machine for articles of elongated shape comprising a traveling conveyor having a plurality of rows of elongated openings therein, the longer dimensions of the openings extending in the direction of travel, longitudinally extending separating strips between the rows of openings and a plurality of projections arranged above the strips and movable in the opposite directions from the conveyor to align the articles with the openings therein.

6. A grading machine for articles of elongated shape comprising a traveling conveyor having a plurality of openings therein elongated in the direction of travel thereof, and aligning members adjacent the sides of said openings for engaging and aligning the conveyed articles with said openings.

7. A grading machine for articles of elongated shape comprising a traveling conveyor having therein a plurality of openings conforming in shape to the articles to be graded, and article arranging members adjacent the sides of said openings for engaging and arranging the conveyed articles to conform with said openings.

WILLIS A. TRECOTT.
